UNITED STATES PATENT OFFICE

97,160

DESIGN FOR A TOTEM POLE AND PICTURE TRANSPOSER TOY

Romy F. Ford, New York, N. Y.

Application July 26, 1934, Serial No. 52,700

Term of patent 3½ years

To all whom it may concern:

Be it known that I, Romy F. Ford, a citizen of the United States, residing at New York, in the county of New York and State of New York, have invented a new, original, and ornamental Design for a Totem Pole and Picture Transposer Toy, of which the following is a specification, reference being had to the accompanying drawing, forming part thereof.

In the drawing:

Figure 1 is an elevational view of a totem pole

and picture transposer toy showing my new design.

Figure 2 is an elevation slightly in perspective, showing the tubular sections of Fig. 1 severed and relaxed from the center post for the purpose of affording a complete view of the surface inscriptions.

I claim:

The ornamental design for a totem pole and picture transposer toy as shown.

ROMY F. FORD.
